UNITED STATES PATENT OFFICE.

LYSANDER O. MAKEPEACE, OF WORCESTER, MASSACHUSETTS.

MANUFACTURE OF IMPRESSION-STITCH SOLES FOR BOOTS AND SHOES.

SPECIFICATION forming part of Letters Patent No. 268,421, dated December 5, 1882.

Application filed September 23, 1882. (No model.)

To all whom it may concern:

Be it known that I, LYSANDER O. MAKEPEACE, of the city and county of Worcester, of the State of Massachusetts, have invented 5 a new and useful Improvement in Impression-Stitch Soles and in the Process of Manufacturing the Same for Boots and Shoes; and I do hereby declare the same to be described in the following specification and represented in the 10 accompanying drawings, of which—

Figure 1 is a top view, Fig. 2 an edge elevation, and Fig. 3 a transverse section, of a sole embodying my invention, the nature of which is defined in the claims hereinafter presented. 15 Fig. 4 is a transverse section of the sole-blank as bent down near its edges preparatory to having a portion of the part bent down removed in order to bring the lower surface of the bent-down part flush with the lower surface or flesh side of the sole.

In making leather soles for being marked around the edge by what are termed by shoemakers "impression-strokes," it, prior to the date of my invention, has been customary to 25 chamfer or bevel the sole upon its hair side where to be marked or impressed, part of the grain-surface being removed with the portion or strip of leather so taken from the sole. Soles so reduced frequently, if not always, present a 30 rough surface or appearance in the part impressed.

The object of my invention is to preserve the grain-surface of the sole entire, in order that after it may have been impressed it shall 35 present or have a better or smoother finish. By "grain-surface" is meant the side or surface from which the hair of the hide may have been removed, the opposite side of the sole being usually termed the "flesh side" or surface.

In carrying out my invention I bend down 40 from its grain side—which is to be supposed to be its upper side—the sole-blank, near its edge and about its sides and toe, in manner as shown in Fig. 4, in which S is the sole-blank, and a b c d the portion bent down at each edge

of the sole with respect to the contiguous portion a d d a. The lower side or surface, b a a b, in Fig. 4 is the flesh side of the leather or sole. Next, or at the same time, or previously, I remove from the part so bent down a strip, e, 50 triangular or substantially triangular in transverse section, so as to bring the entire lower surface of the sole in one plane, or the lower surface of the remainder of the part bent down flush with the contiguous lower surface of the 55 sole. The sole thus treated is to have the upper surface of the part bent down stitch-impressed, as shown at f in Figs. 1 and 2. The bending down of the sole and the paring and impressing of it I usually accomplish at one 60 and the same time, or thereabout, by a machine especially made for the purpose.

I claim—

1. The described improvement in the process of treating a boot or shoe sole, such consisting 65 in bending such sole down at its edge in manner as set forth, and embossing or stitch-impressing the upper side of the part bent down, and paring or reducing the lower portion of such part, so as to bring the entire lower sole- 70 face essentially into one plane, as explained.

2. A boot or shoe sole embossed or stitch-impressed on its grain-surface, along the edge thereof, and having the part of such surface so 75 embossed or stitch-impressed at an obtuse angle with the next adjacent part of the said grain-surface.

3. A boot or shoe sole embossed or stitch-impressed on its grain-surface, along the edge thereof, and having the part of such surface so 80 embossed or stitch-impressed at an obtuse angle with the next adjacent part of said grain-surface, and also having the opposite or flesh side essentially in one plane, or flush from edge to edge, as represented.

LYSANDER O. MAKEPEACE.
